COMBINATION TOOTHBRUSH, TOOTHPASTE AND CUP HOLDER

Edward L. Kimerer, Marysville, Calif.

Application March 20, 1957, Serial No. 45,364

Term of patent 14 years

(Cl. D4—3)

FIG. 1.

FIG. 2.

FIG. 3.

FIG. 4.

FIG. 5.

FIG. 6.

Fig. 1 is a perspective view of a combination toothbrush, toothpaste and cup holder showing my new design with the door open;

Fig. 2 is another perspective view taken from another vantage point and also showing my design with the door open;

Fig. 3 is a reduced scale front elevational view of my new design with the door closed;

Fig. 4 is a top plan view of Fig. 3;

Fig. 5 is a right side elevational view of Fig. 3; and

Fig. 6 is a bottom plan view of Fig. 3.

I claim:

The ornamental design for a combination toothbrush, toothpaste and cup holder, substantially as shown.
